UNITED STATES PATENT OFFICE.

FREDERIC H. LANE, OF BOSTON, MASSACHUSETTS.

DESIGN FOR A TOY BLOW-PIPE.

Specification forming part of Design No. 7,501, dated June 23, 1874; application filed February 16, 1874.
[Term of Patent 3½ years.]

To all whom it may concern:

Be it known that I, FREDERIC H. LANE, of Boston, Massachusetts, have invented an Improvement in Design for Toy, of which the following is a specification:

The drawing herewith fully illustrates the character of the improvement in design, and is referred to in the following description.

The tube J, slightly knobbed at the extremity K, has a deep curve or loop, H D,

and terminates in the straight portion A, connected to the shallow receptacle G.

What I claim as my invention is—

The design for a toy blow-pipe, herein described and shown.

FREDERIC H. LANE.
